Primary Examiner — Kevin K Rudzinski*Assistant Examiner* — Clare Ann Gannon(74) *Attorney, Agent, or Firm* — Shumaker, Loop & Kendrick, LLP(57) **CLAIM**

The ornamental design for an adjustable belt loop fastening device, as shown and described.

DESCRIPTION

FIG. 1 is a top perspective view of the new design for an adjustable belt loop fastening device;

FIG. 2 is a bottom perspective view thereof;

FIG. 3 is a front view thereof;

FIG. 4 is a top view thereof;

FIG. 5 is a back view thereof;

FIG. 6 is a right side view thereof, with the left side being a mirror image of the right side;

FIG. 7 is a bottom view thereof; and,

FIG. 8 is a perspective view thereof, shown in a closed configuration in a position of use on two belt loops.

The broken lines in the drawings depict environment that forms no part of the claimed design.
